HIGH FREQUENCY ELECTRICAL OSCILLATION GENERATOR AND AMPLIFIER

Ernest Green, Chelmsford, and Frederick Gawn Robb, Danbury, England, assignors to Radio Corporation of America, a corporation of Delaware

Application July 19, 1932, Serial No. 623,360
In Great Britain August 18, 1931

8 Claims.

(Cl. 179—171)

This invention relates to high frequency circuit arrangements and has for its object to provide an improved high frequency circuit and, more particularly, an improved circuit for use on very short waves of the order of 30 metres or less wherein means are provided for eliminating oscillations of undesired frequency.

As is well known, one of the difficulties experienced in high frequency oscillation generators and the like is that there is a liability for the setting up of frequencies other than the desired or main oscillation frequency, and various proposals have been made for eliminating such undesired frequencies. For example in the previous British Patent No. 148,447 the setting up of oscillations of an undesired frequency in a thermionic generator in which oscillations of either of two frequencies may be produced is prevented by the interposition of an auxiliary condenser or inductance or resistance or a separate circuit synchronized to the undesired frequency. Similarly, reference may be made to the previous British patent specification No. 148,445. Further, various proposals have been made to eliminate what are known as parasitic oscillations, these proposals consisting in the main in inserting damping resistances in the probable path of parasitic oscillations. For antiparasitic arrangements of this general kind, reference may be made to United States Patents Nos. 1,830,164, 1,787,309, and 1,954,589.

It has now been found that in short wave oscillation generating and amplifying circuits, there is a great tendency for the setting up of parasitic oscillations when the constants of the circuit are such that the natural frequency of such parasitic oscillations equals or approximates to a harmonic of the main or desired oscillation frequency. The object of the present invention is to provide means for avoiding this particular difficulty, and according to this invention adjustable reactive means are provided for altering the natural frequency of the circuit generating or tending to generate parasitic oscillations so that the natural frequency is not or does not approximate to a harmonic of the main oscillation frequency.

The present invention may be employed in conjunction with any other means for suppressing parasitic oscillations.

Figure 1 of the accompanying drawing illustrates one way of carrying out the invention as applied to an amplifier consisting of a single thermionic valve to whose grid circuit are applied the oscillations to be amplified, and as will be seen an added inductance, preferably variable,

is provided in accordance with the invention in the parasitic oscillation circuit. Figure 2 represents a variation of this arrangement. Figure 3 illustrates one way of applying the principles of the present invention to a two valve circuit, and Figures 4 and 5 are further embodiments of the invention as applied to two valve circuits.

Referring to Figure 1 which only shows those parts of the circuit relevant to the present invention the amplifier valve circuit comprises a valve 1 having in its grid circuit the usual coil 2 for the application of the "drive" and having in its plate circuit a parallel resonant circuit 3, 4, tuned to the main or working frequency. The end of this resonant circuit remote from the plate is connected to the grid through a neutralizing condenser 5 and (in accordance with this invention) a small variable inductance 6 in series. This small variable inductance is adjusted in value to remove parasitic oscillations.

In a variation of this arrangement the small inductance is as shown in the accompanying Figure 2 shunted by a tuning condenser 7 in series with a resistance 8 so that the inductance, condenser, and resistance together constitute a damped tuned circuit. The provision of the resistance renders the adjustment less critical.

In a further arrangement shown in the accompanying Figure 3 an amplifier consists of two valves 1, 1' whose plates are connected together through a parallel tuned circuit 3, 4, anode feed being applied to the mid point of the coil of this circuit. The plate of each valve is also connected to the grid of the other through a condenser 5 or 5' and small variable inductance 6 or 6' in series with one another, the small variable inductances being adjusted for the elimination of parasitics. The drive is applied via coil 2' as shown, to the two grids at the junction points of the small variable inductances and the condensers in series therewith. If desired, the small variable inductance may be replaced by tuned circuits consisting each of inductance shunted by capacity and resistance in series, as in the single valve amplifier shown in Figure 2.

If desired, and as shown in the accompanying Figures 4 and 5 the adjustment devices may be in a separate loop circuit. In Figures 4 and 5 the plate of each valve 1 or 1' is connected to the grid of the other through a condenser. Coupled to the two grid leads is a loop circuit across which parasitic eliminating adjustment means is symmetrically shunted. The coupling of this loop circuit to the grid leads may be made

as shown in Figure 4 by employing as the loop circuit a loop of wire or conductor 9 running parallel to the grid wires in such manner that the coupling thereto is equal i. e. the coupling to one grid wire is equal to the coupling to the other. The adjustment device comprises a resistance 10 and a condenser 11 in series and is connected symmetrically across the loop. In the arrangement shown in Figure 5 the coupling of the loop circuit containing the adjustment device to the grid wires is made by means of coils. In this arrangement each grid wire contains a small coupling coil 12 or 12' coupled to one of a pair of smaller coils 13 or 13' in the loop circuit. As before, the adjustment device consists of a condenser 11 and resistance 10 in series connected symmetrically across the loop. The arrangements shown in Figures 4 and 5, wherein the anti-parasitic adjustment devices are across a loop circuit, present the advantage that the adjustment devices which serve to vary the tuning of the circuit tending to set up parasitic oscillations have no reaction back on the main oscillations while at the same time there is close coupling as regards the parasitic oscillations.

Having now particularly described and ascertained the nature of our said invention and in what manner the same is to be performed, we declare that what we claim is:

1. A high frequency circuit arrangement comprising an electron discharge device having a control electrode and an anode in circuit with a tuned output circuit, a direct conductive connection from one terminal of said output circuit to said anode, a connection including a condenser from the other terminal of said output circuit to said control electrode, said output circuit and connections having constants such that the natural frequency of parasitic oscillations approximates a harmonic of the desired frequency, and adjustable reactive means included in said last connection for preventing parasitics whereby said natural frequency of the parasitic oscillations is altered to a value which does not approximate to a harmonic of the desired frequency.

2. An arrangement as defined in claim 1, characterized in this, that said adjustable reactive means includes a variable inductance.

3. A high frequency circuit arrangement comprising an electron discharge device having a control electrode and an anode in circuit with a tuned output circuit, a direct conductive connection from one terminal of said output circuit to said anode, a connection including a condenser from the other terminal of said output circuit to said control electrode, said output circuit and connections having constants such that the natural frequency of parasitic oscillations approximates a harmonic of the desired frequency, and means comprising an inductance shunted by a condenser and a resistance in series included in said last connection for preventing parasitics whereby said natural frequency of the parasitic oscillations is altered to a value which does not approximate to a harmonic of the desired frequency.

4. An arrangement as defined in claim 3, characterized in this, that said last means comprises a damped tuned circuit having an adjustable in-

ductance shunted by a variable condenser and a resistance in series.

5. A high frequency circuit arrangement comprising an electron discharge device having a control electrode and an anode in circuit with a tuned output circuit, a direct conductive connection from one terminal of said output circuit to said anode, a connection including a condenser from the other terminal of said output circuit to said control electrode, said output circuit and connections having constants such that the natural frequency of parasitic oscillations approximates a harmonic of the desired frequency, and adjustable reactive means in circuit with said last connection for preventing parasitics.

6. A high frequency circuit arrangement comprising an electron discharge device having a control electrode and an anode in circuit with a tuned output circuit, a direct conductive connection from one terminal of said output circuit to said anode, a connection including a condenser from the other terminal of said output circuit to said control electrode, said output circuit and connections having constants such that the natural frequency of parasitic oscillations approximates a harmonic of the desired frequency, and adjustable reactive means in circuit with said last connection for preventing parasitics, comprising a parallel tunable loop circuit having a variable condenser and a resistance in series, and a connection in parallel with said series combination of condenser and resistance, said loop circuit being inductively coupled to a connection which extends from said output circuit to said control electrode.

7. A high frequency circuit arrangement comprising an electron discharge device having a control electrode and an anode in circuit with a tuned output circuit, a direct conductive connection from one terminal of said output circuit to said anode, a connection including a condenser from the other terminal of said output circuit to said control electrode, said output circuit and connections having constants such that the natural frequency of parasitic oscillations approximates a harmonic of the desired frequency, and adjustable reactive means in circuit with said last connection for preventing parasitics comprising a parallel tunable loop circuit having a variable condenser and a resistance in series, and a connection in parallel with said series combination of condenser and resistance, said loop circuit being inductively coupled to a connection which extends from said output circuit to said control electrode.

8. A high frequency circuit arrangement comprising an electron discharge device having a control electrode and an anode in circuit with a tuned output circuit, a direct conductive connection from one terminal of said output circuit to said anode, a connection including a condenser from the other terminal of said output circuit to said control electrode, said output circuit and connections having constants such that the natural frequency of parasitic oscillations approximates a harmonic of the desired frequency, and adjustable reactive means in circuit with said last connection for preventing parasitics comprising a parallel tunable loop circuit having a variable condenser and a resistance in series, and an inductance coil in parallel with said series combination of condenser and resistance, said loop circuit being inductively coupled through said inductance coil to said connection which extends from said output circuit to said control electrode.

9. The combination with a push-pull circuit comprising two electron discharge devices whose corresponding anode, cathode and control electrodes are respectively connected together, and neutralizing condensers individually cross-connected between the control electrodes of said devices and the anodes of the associated devices, of an inductance directly connected between each neutralizing condenser and its associated control electrode to which it is directly connected, and a tuned input circuit coupled to both of said control electrodes at the junction points of the neutralizing condensers and the respective inductance coils.

ERNEST GREEN.
